DESIGN FOR A NAPKIN

Ralph Rubino, New York, N. Y.

Application March 20, 1939, Serial No. 83,718

Term of patent 14 years

To all whom it may concern:

Be it known that I, Ralph Rubino, a citizen of the United States, residing at New York city, in the county of Bronx and State of New York, have invented a new, original, and ornamental Design for a Napkin, of which the following is a specification, reference being had to the accompanying drawing, forming a part thereof.

The figure is a plan view of a napkin, showing my design, the initial "A" in one corner of the napkin being indicated in dotted lines.

I claim:

The ornamental design for a napkin, as shown and described.

RALPH RUBINO.
